UNITED STATES PATENT OFFICE.

GEORGE S. COMSTOCK, JR., OF STEELTON, PENNSYLVANIA, ASSIGNOR TO BETHLEHEM STEEL COMPANY, OF BETHLEHEM, PENNSYLVANIA, A CORPORATION OF PENNSYLVANIA.

APPARATUS FOR HANDLING PULVERULENT MATERIAL.

Application filed April 14, 1920. Serial No. 373,803.

To all whom it may concern:

Be it known that I, GEORGE S. COMSTOCK, Jr., a citizen of the United States, and residing at Steelton, Dauphin County, State of Pennsylvania, have invented certain new and useful Improvements in Apparatus for Handling Pulverulent Material, of which the following is a specification.

The general object of this invention is to provide an improved pneumatic apparatus for handling pulverulent material, particularly to provide an apparatus of this character adapted to be used for gathering separated small bodies or deposits of coal or coke dust which form rapidly where coal or coke are handled in large quantities, as for instance around blast furnaces, and conveying this dust or braize to a bin or receptacle from which it may from time to time be discharged in larger quantities. The apparatus may be used, however, in other ways if desired, as in unloading cars or boats loaded with grain.

An important feature of the invention is the novel intake nozzle which is provided for each of the intake tubes of the apparatus and which is so designed that it will not become clogged or choked with the material into which the nozzle is thrust and thus impede the working of the apparatus.

This nozzle is so constructed that a portion of its mouth or intake opening is covered by a shield or guard and to this portion of the mouth air from the rear end of the nozzle is conducted. In other words, the mouth of the nozzle is divided, one portion being for a mixture of air and pulverulent material and the other portion for air alone, and a shield is provided, having an air inlet in rear of the mouth of the nozzle for bringing air to its mouth. By this means a certain supply of air to the intake nozzle is assured, notwithstanding the possibility of the clogging of the opening through which the pulverulent material enters, and it is therefore impossible for the intake tube to become clogged at other points along its length due to insufficiency of air for conveying purposes. Other objects of the invention, and advantages thereof, will appear from the description and from the drawings.

In the drawings:

Figure 1 illustrates in side elevation one embodiment of the invention as installed adjacent the base of a blast furnace;

Figure 2 is a perspective view of the suction inlet nozzle;

Figure 3 is a longitudinal sectional view through the inlet nozzle;

Figure 4 is a section along the line 4—4 of figure 3;

Figure 5 is a section along the line 5—5 of figure 1 to a larger scale; and

Figure 6 is a section along the line 6—6 of figure 5.

The bin or receiver 10 is positioned conveniently near the base of the blast furnace and near the coal handling platform or mechanism, and is connected by means of 70 a conduit 11 to an air pump 12 which, in the operation of the apparatus, continually tends to exhaust the air within the same.

Supported upon the bin 10 and outside thereof near its upper end, is a valve casing 75 13 having passages 14 and 15 therethrough, the inner ends of which open into the interior of the bin and the outer ends of which are connected to conveying tubes 16 and 17 respectively. A sliding valve 18 movable transversely in a slot provided in the valve casing is adapted to bring either but not both of said conveying tubes into communication with the interior of the bin 10. As illustrated in Figures 5 and 6, the ports in valve 18 are so spaced that when one of the passages to the valve is open the other must necessarily be closed. By this construction, it is possible for a plurality of conveying tubes to be connected to a common receiver or bin having a vacuum pump of only moderate size, the pump being only of such size as to be capable of operating one tube at a time. It is obvious that to operate a number of tubes simultaneously, a large sized pump would be required, which would involve not only considerable expense in installation but large operation costs.

To the lower end of each of the tubes 16 and 17 is secured a novel form of suction inlet nozzle, clearly illustrated in Figures 2, 3 and 4. This nozzle comprises essentially a tubular portion 19 having a circular inlet opening 20 at its forward end and

22 having secured to its outside a shield 21 which extends parallel thereto and around in front of the inlet opening 20. Preferably this shield 21 covers up one-half of 5 the inlet opening and it forms with the outside of conduit 19 a second conduit for leading air to the opening 20, the rear end of this second conduit being unobstructed at all times.

10 In the operation of the apparatus the suction inlet nozzle on the end of that tube which is connected to the interior of the bin is thrust into a quantity of pulverulent material so that the inlet opening 20 is below 15 the surface thereof. The current of air rushing into the tube because of the partial vacuum existing in the receiving bin 10 carries with it powdered or granular material through that half of the opening 20 which 20 is not covered by the shield 21. In case this portion of the opening becomes clogged with the material being conveyed, the air supplied through the second conduit to the main conduit, is sufficient to prevent the intake tube from becoming clogged at any 25 other point along its length due to lack of sufficient quantity of air for carrying purposes. The entrance to the conduit enclosed by the shield 21 is never obstructed 30 being at no time inserted beneath the surface of the material to be conveyed. The system, therefore, can never become choked, there being always a sufficient amount of air passing to carry the braize or material then 35 in the tube, when the obstruction of the nozzle occurs, into the receiving tank. The air passing through the unobstructed half 40 of the opening 20 will also tend to clear away the obstruction of the other part of the opening.

Various changes may be made in the structure and arrangement of parts of the invention and I do not limit myself therefore to the exact form shown and described.

45 Having thus described the invention what

is claimed as new and desired to be secured by Letters Patent is:

1. A suction nozzle for handling pulverulent material comprising an open ended tube, one end of which constitutes an intake 50 opening for pulverulent material and air, and the other end of which is adapted to be connected to a suction hose, and a second tube secured to one side of said first tube and extending forwardly beyond the intake 55 opening of the first tube, said second tube having its rear end open to the air and its forward end closed and extending in front of a portion of the intake opening of the first tube to constitute a guard preventing 60 the entrance of pulverulent material into said portion of the intake opening, and to conduct air to said intake opening to prevent clogging of the same by pulverulent 65 material.

2. A suction nozzle for handling pulverulent material comprising an open ended tube, one end of which constitutes an intake 70 opening for pulverulent material, and the other end of which is adapted to be connected to a suction hose, and a second tube fixed to said first tube, and having its axis parallel to that of the first tube, and spaced therefrom a distance less than the sum of the radii of the two tubes, said second tube 75 extending forwardly beyond the intake opening of the first tube and having its rear end open to the air and its forward end closed and extending in front of a portion 80 of the intake opening of the first tube to constitute a guard preventing the entrance of pulverulent material into said portion of the intake opening and to conduct air to said opening to prevent clogging of the same by pulverulent material.
